(57) **CLAIM**

The ornamental design for a disposable microwave oven food cover with vents, as shown and as described.

DESCRIPTION

FIG. 1 is a front perspective view of a disposable microwave oven food cover with vents showing my new design; FIG. 2 is right side view thereof; FIG. 3 is a left side view thereof; FIG. 4 is a top view thereof; FIG. 5 is a bottom view thereof; FIG. 6 is a front perspective view of the disposable microwave oven food cover with vents as shown in FIG. 1 in a folded configuration; FIG. 7 is a front view thereof in a folded configuration; FIG. 8 is a rear view thereof in a folded configuration; FIG. 9 is a side view thereof in a folded configuration where the opposite side is a mirror image; FIG. 10 is a top view thereof in a folded configuration; and, FIG. 11 is a bottom view thereof in a folded configuration. The broken lines included in the Figures illustrate environmental structure and form no part of the claimed design.
